PENDANT FOR LIGHTING FIXTURE

Julius Friedman and Carl Wellhofer, Philadelphia, Pa., assignors to Lighting Corporation of America, Philadelphia, Pa., a corporation of Pennsylvania

Filed Aug. 7, 1968, Ser. No. 13,056

Term of patent 7 years

Int. Cl. D26—99

U.S. Cl. D48—14

FIGURE 1 is a front elevational view of a pendant showing my new design;

FIGURE 2 is a top plan view thereof;

FIGURE 3 is a bottom plan view;

FIGURE 4 is a side elevation view;

FIGURE 5 is an end profile view taken on line 5—5 of FIGURE 2;

FIGURE 6 is a rear elevation view;

FIGURE 7 is a cross-sectional view taken along the line 7—7 of FIGURE 1;

FIGURE 8 is a cross-sectional view taken along the line 8—8 of FIGURE 1.

We claim:

The ornamental design for a pendant for lighting fixture, substantially as shown and described.
